UNITED STATES PATENT OFFICE.

KARL GAMMEL, OF CLEVELAND, OHIO, ASSIGNOR TO THE CLEVELAND MACARONI COMPANY, OF CLEVELAND, OHIO, A CORPORATION OF OHIO.

PROCESS OF DRYING MACARONI.

1,300,718.

Specification of Letters Patent. Patented Apr. 15, 1919.

Application filed March 25, 1911, Serial No. 616,937. Renewed September 14, 1917. Serial No. 191,498.

To all whom it may concern:

Be it known that I, KARL GAMMEL, a subject of the Emperor of Germany, residing at Cleveland, in the county of Cuyahoga and 5 State of Ohio, have invented certain new and useful Improvements in Processes of Drying Macaroni, of which the following is a specification.

Heretofore much difficulty has been experienced in drying edible pastes, such as macaroni and similar products, in apparatus employed for drying such materials, because of the tendency of the several pieces or lengths of the material to stick together by 10 reason of the large amount of moisture contained therein, and the object of this invention is to provide a process whereby this tendency may be overcome, and the pieces or lengths of the material can be handled in 15 bulk without injury thereto. A further object of the invention is to shorten the length of time heretofore required to dry edible pastes. The various other objects of the invention will be more fully set forth in the 20 following description of my improved process, which consists in the new and novel steps hereinafter set forth and claimed.

When edible pastes, such as macaroni and similar products, are first removed from the 25 press, they are in an extremely soft and plastic condition, and contain a large amount of moisture, either in the form of a liquid deposited on the surface or contained within the goods. My improved process consists 30 essentially in removing all of the excess water both on the exterior of the lengths of macaroni, which is made in the form of tubes, and likewise from the interior of said tubes, and also drying both the interior and 35 exterior portions adjacent to the exterior and interior surfaces of the tubes and then gradually drying the goods under suitable conditions until the goods are thoroughly dry throughout.

40 In the accompanying drawings, showing one form of apparatus adapted for carrying out my improved process,

Figure 1 is a vertical sectional view through the primary chamber of an apparatus suitable for carrying out my improved process with the chassis shown in side elevation; and

Fig. 2 is a vertical sectional view through the secondary chamber of the apparatus.

45 Referring to the drawings which show

but one means for carrying out the process, the primary drying chamber 1 is preferably rectangular in shape, and has one of its sides 2 preferably formed of a flexible material, such as canvas, mounted upon rollers 3 60 whereby it may be raised and lowered. The chamber is adapted to receive a chassis 4, which contains the material 5 to be dried, which is placed therein upon sticks or hangers 7. A fan 8 is secured in the side of the 65 receptacle opposite the flexible side 2. Said fan may be of any well known construction, which will permit the same to be reversed, so that the air can be forced or drawn through the receptacle as desired. The fan 70 when forcing the air into the receptacle may draw its relatively dry air from any suitable source. If the normal atmosphere is too moist it may be connected with any air drying oven 8' or the air may be drawn through 75 any suitable mechanical or chemical drying agent. When the fan is drawing the air from the receptacle the humidity of this air will depend in part upon the amount of moisture present in the receptacle. The sec- 80 ondary drying chamber 9 is provided with a wing 10 or any suitable mechanism for rapidly producing currents in opposite directions through the material contained therein, and is also provided with a valve controlled 85 inlet 11 and outlet 12, whereby a small quantity of air may be drawn into the chamber and a corresponding quantity of moist air may be expelled therefrom upon each stroke of the wing, so that the body of air will be 90 given an advancing movement within the chamber. This secondary drying chamber may be substantially the same as the apparatus described and claimed in U. S. Patent No. 932,695 dated August 31, 1909, granted 95 to me for drying apparatus, and no further description thereof is necessary. This invention resides solely in the process and it will be understood that various changes and modifications may be made in the particular 100 form of apparatus shown, it being obvious that the process may be carried out in chambers of different construction.

In practising my improved process the macaroni or similar product, immediately 105 upon issuing from the press, is hung upon the sticks or hangers, and is then subjected to the primary drying. A current of air of considerable velocity and relatively low humidity is then forced through and around 110

the goods by means of the fan, until a portion of the excess moisture is extracted from the goods. Preferably the fan is then reversed and the air is drawn from the goods, 5 thus creating a current in the opposite direction through and around the goods which may be of less velocity and also a higher humidity than the current which is forced through the goods. While the weaker air 10 current which is being drawn through the goods the excess water comes to the surface of the goods, which become quite moist, and thereupon the direction of the current may be reversed and the air forced through the 15 goods until the surface of the goods have been dried. This operation is continued until approximately 60% of the water contents of the goods has been removed.

After a considerable proportion of the 20 water contents of the goods has been removed, as for example 60%, the pieces or lengths of macaroni lose their flexibility and become quite hard on the surface. Thereupon they are removed to the secondary 25 drying chamber, where they are subjected to the action of currents of air which alternate with considerable rapidity and have a relatively high humidity. The process of drying, which is extremely rapid in 30 the primary drying chamber, is considerably slower in the secondary chamber, but the drying is carried on evenly throughout the goods, since the moist body of air in contact therewith tends to keep the outer surface in 35 a moist and pliable condition. The humidity of the air in the secondary chamber is controlled in any suitable manner as by the quantity of fresh air admitted and the quantity of moist air expelled through the 40 pipes 11 and 12 and is always sufficiently high to prevent the macaroni or similar product from bursting or cracking.

In drying macaroni and similar pastes in machines, it has been found difficult to eliminate the great quantity of water which was evaporated soon after the goods were placed therein, and furthermore the necessity for placing the goods close together in such apparatus caused the goods to sweat thus increasing the amount of water given off in the first part of the operation. By means of the present process all of the excess water is removed before the goods are placed in the secondary drying chamber, and consequently 55 there is no tendency for the goods to stick together, and the sweating of the goods is also avoided. Consequently the process of drying is shortened very materially, and a better product is also obtained.

60 I claim as my invention:

1. The process of drying macaroni and similar edible pastes which consists in subjecting the goods to the action of a current of

air having considerable velocity and relatively low humidity and then to a current of 65 air having less velocity and higher humidity until the excess moisture contained in the goods is removed, and then subjecting the goods to a current of air alternately moving in opposite directions and having a relatively 70 high humidity until the drying process is completed, all of said currents having a humidity below their saturation point.

2. The process of drying macaroni and similar edible pastes which consists in alternately subjecting the goods to the action of currents of air of relatively low and of relatively high humidity until approximately 60% of the water contents of the goods has been removed, and then subjecting the goods 80 to the action of alternating currents of air having a relatively high humidity but below the saturation point, until the drying process is completed.

3. The process of drying macaroni and similar edible pastes which consists in subjecting the goods to a current of air of relatively low humidity having relatively high velocity, then subjecting said goods to the action of a current of air of relatively low 90 humidity and relatively low velocity, and then subjecting the goods to the action of a rapidly alternating current of air of relatively high humidity but below the saturation point, substantially as described.

4. The process of drying macaroni, which consists of subjecting the goods to a preliminary drying by means of sustained air currents of different velocities and degrees of humidity and then to a secondary drying 100 by means of alternating air currents of approximately uniform humidity, said air currents having a humidity below their saturation points.

5. The process of drying macaroni, which 105 consists in subjecting the goods to a preliminary drying by air currents of considerable velocity but different rates of movement and degrees of humidity; and then to air currents of low velocity and substantially uniform humidity, said air currents having a humidity below their saturation points.

6. The process of drying macaroni which 115 consists in subjecting the goods to a relatively rapid preliminary drying in the presence of air having relatively low humidity and then to a relatively slow drying in the presence of air currents having relatively high humidity but below the saturation point of the air.

This specification signed and witnessed this 13th day of March, A. D. 1911.

KARL GAMMEL.
